UNITED STATES PATENT OFFICE

162,485

CARRIER FOR VACUUM CLEANER
ATTACHMENTS

James W. Sheker, Fort Dodge, Iowa

Application November 9, 1949, Serial No. 5,947

Term of patent 7 years

(Cl. D9—5)

To all whom it may concern:

Be it known that I, James W. Sheker, a citizen of the United States of America, residing at Fort Dodge, in the county of Webster and State of Iowa, have invented a new, original, and ornamental design for a Carrier for Vacuum Cleaner Attachments, of which the following is a specification, reference being had to the accompanying drawing, forming a part thereof.

In the drawing:

Figure 1 is a side elevational view of a carrier for vacuum cleaner attachments, showing my new design.

Figure 2 is a plan view of the same.

Figure 3 is a perspective view, the handle shown in Figs. 1 and 2 being omitted for convenience of illustration.

I claim:

The ornamental design for a carrier for vacuum cleaner attachments, as shown and described.

JAMES W. SHEKER.
